UNITED STATES PATENT OFFICE

FREDERIC W. HILD, OF LOS ANGELES, CALIFORNIA

WELL PUMPING SYSTEM

Application filed March 15, 1928. Serial No. 261,808.

This invention relates generally to pumping systems and more particularly to long-stroke pumping systems for oil wells and the like.

6 In my copending application, Serial No. 193,224, filed May 21, 1927, I have shown a long-stroke pumping system comprising apparatus and control which is particularly adapted to be utilized for pumping oil wells 10 and the like, wherein a pair of motors are connected to two sun-gears, or end elements, of a planetary gear system forming a differential gear set. The middle element, or planetary member, of the differential gear set is connected to operate a cable winding drum, which actuates a cable that is connected to a pump plunger. A reciprocatory motion is imparted to the plunger by periodically reversing the direction of rotation of the 20 drum. In this particular instance, the reversing of the drum is effected by alternately changing the relative speeds of the motors.

25 My copending application, Serial No. 221, 418, filed September 23, 1927, shows another long-stroke pumping system wherein a special form of differential gear transmission with a single driving motor is utilized to actuate a cable winding drum to which the pump plunger is connected. In this instance, reversal 30 of the drum is effected by reversing the direction of rotation of the motor by means of an oscillator mechanism interposed between the drum and a reversing type controller.

35 The present invention provides a long-stroke pumping system embodying a part of the apparatus shown in the latter application, and additional apparatus that will be described in detail in the subsequent paragraphs of this specification.

40 Among the many important problems confronting the oil industry is that of economically and efficiently pumping the deep wells that are now in use. There are two general methods of obtaining oil from the ground, one, mechanical pumping, the other, raising the oil by compressed gas or air.

45 Mechanical pumping is in greater use and is in general, the more economical method. Long-stroke mechanical pumping systems, as provided in the hereinbefore mentioned co-

pending applications, eliminates many of the difficulties and improves the efficiency of mechanical oil pumping systems.

The hazard of back pressure on the producing sands inherent in the gas or air lift, is 55 not present with mechanical pumping which on the contrary augments the natural flow of the fluid into the well by exerting suction action. The difficulties due to variable and uncertain submergence attendant upon the 60 gas lift method are absent from mechanical pumping.

On the other hand, the gas lift increases the recovery of natural gasoline. Furthermore, the gas lift can continuously apply its 65 lifting power, whereas the single acting mechanical pump is limited to one half the time, namely the lifting stroke.

70 It is the object of this invention to provide a pumping system combining the best features of the gas lift and the mechanical pump and which shall have mutual and automatic control of both.

75 The introduction of compressed gas at a point below the fluid level in a well, results in apparently stretching the fluid column without increasing its weight, by converting the fluid into a chain of bubbles reaching to the discharge line at the surface. Consequently in the pumping system of this invention, the weight to be moved and hence the size and strength required of the mechanical pumping means will be greatly lessened.

80 Another object of the invention is to provide for controlling the operation of a reciprocating pump plunger by means of an auxiliary work device connected in the pumping system and disposed to be driven by the energy stored in the plunger during the 85 pumping stroke.

85 Another object of the invention is to provide for operating a plurality of work devices from the same motor and causing the work devices to control the operation of each 90 other.

95 This invention accordingly is disclosed in the embodiment thereof shown in the accompanying drawings and comprises the features of construction, the combination of elements, and the arrangement of parts which will be 100

exemplified in the structure hereinafter set forth, and the scope of the application of which will be indicated in the claims.

Referring to the drawings, Figure 1 is a view in elevation, and partly in section, of a plunger type pumping system constructed in accordance with the present invention;

Fig. 2 is a cross-sectional view in elevation of a coupling shown in Fig. 1; and

Fig. 3 is a plan view of the pumping system shown in Fig. 1 with the addition of other apparatus to form a complete system embodied in the present invention.

Referring to Fig. 1 of the drawings, apparatus embodying the present invention may be applied to an oil well having the usual string of casing 1 suspended therein, the lower end of the casing terminating at the point near the strata of oil bearing sand 2.

In order to lift the fluid from the strata of oil bearing sand to the surface of the ground, a plunger pump is provided comprising a string of pump tubing 3 within the casing 1 and a working barrel or pump cylinder 4 to which is attached a perforated strainer 5 for admitting oil or other liquid, and excluding sand from the working barrel 4.

In order to raise the fluid which enters the working barrel 4, a plunger 6 with a ball valve 7 is provided and disposed to be reciprocated within the working barrel 4 by means of a string of pump rods 8, attached to a polish rod 9 which extends through a suitable stuffing box 11.

The usual type of standing valve 12 is provided in the lower extremity of the working barrel 4 to permit the fluid to enter the pump barrel 4 and to prevent a return flow of fluid from the barrel 4 during the downward stroke 40 of the plunger.

As will be observed from the drawings, a second string of well casing 14 extends from the surface to a point near the working barrel 4 where it is coupled to the tubing 3 by means of a reducer coupling 15.

The constructional details of the coupling 15 are shown in Fig. 2. The upper end of the tubing 3 is attached to the lower reduced end of the coupling 15 at 16, making a gas or liquid tight joint. The upper end of the coupling is provided with screw-threads at 17, disposed to engage the threaded portion of the well casing 14, and is also provided with a cylindrical seat 18 to receive the lower unthreaded end of the tubing 3. The lower portion of the tubing 3 contains a plurality of perforations, shown at 19 to afford communication from the tubing 3 into the casing 14.

The auxiliary casing 14 is provided with a cap 21 at its upper end which is provided with a suitable packing through which the tubing 3 passes. As shown, this particular construction forms an annular space between the casing 14 and tubing 3 that is utilized to

retain gas or air under pressure, as will be referred to in greater detail hereinafter.

Natural gas or air under pressure may be admitted to the casing 14 through a pipe 22 and valve 23, which are secured to the casing cap 21 by means of the flange coupling 24. A pressure gauge 25 is provided for indicating the gas or air pressure within the casing 14.

The pump tubing 3, which extends through the stuffing box in the casing cap 21 is provided with a cap 26 which is adapted to support the stuffing box 11. The fluid which is raised by the plunger 6, or by the combined action of the plunger and compressed air or gas, is discharged from the cap 26 through the valve 27 and pipe 28 into any suitable receptacle such, for example, as a tank or an oil gathering line.

A pipe nipple which connects the valve 27 to the tubing cap 26 is tapped to receive an air vent pipe 29 that is provided with a controlling valve 31, the purpose of which will be described in detail hereinafter.

In order to impart a reciprocating motion to the pump plunger 6, the polish rod 9 is connected to a rotatable drum 32 by means of a flexible cable or wire line 33 which passes over a sheave wheel 34. The sheave wheel 34 may be supported in any convenient manner such, for example, as by an ordinary well derrick or by any other suitable structure.

In order to actuate the drum 32, a suitable motor driven reduction gear mechanism 35 is provided, together with suitable control apparatus, as will be described more in detail hereinafter.

For a more complete understanding of the arrangement and operation of the pumping system, reference may now be had to Fig. 3 of the drawings.

As shown, the cable winding portion of the drum 32 is mounted upon a shaft 36 which is rotatably supported by suitable bearings 37. The drum shaft 36 is provided at opposite ends with jaw clutches 38 and 39 respectively, that are disposed to engage the sprocket wheels 41 and 42, rotatably mounted on the shaft 36.

In order to hold the hoist drum 32 in any desired position when the pump is not in operation friction brake bands 43 are provided. The operation of the bands 43 may be controlled in any desired manner such, for example, as by a well known manually operated lever system or an electromagnetic control.

The sprocket 41 is connected by a chain 44 to the driving sprocket 45 of the gear mechanism 35. In this embodiment of the invention, the gear mechanism shown, is a modified form of the well known double drive differential type that is used for earth

boring and the like, and is adapted for single motor operation.

The gear mechanism 35 comprises a pair of bevel sun-gear wheels 46 and 47, rotatably mounted on a shaft 49. A spur gear 51 is securely keyed to the sun gear 46 and is disposed to mesh with the driving pinion 52 which is mounted upon the drive shaft 53. The sun-gear wheels 46 and 47 are each provided with an extended sleeve portion which serves as quill bearings surrounding the shaft 49 and are rotatably supported in suitable bearings in the gear case 54, as shown. The sleeve portion of the sun gear 47 is extended beyond the gear case 54 to receive the sprocket 55 which is securely keyed thereon.

The planetary element of the differential mechanism comprises spider 56, and a plurality of bevel pinion wheels 57 rotatably mounted on pinion shafts 58 and disposed to mesh with the sun-gear wheels 46 and 47. The spider 56 is secured to the shaft 49 which is rotatably mounted in the sleeve extensions of the sun-gear wheels 46 and 47. In order to control the operation of the differential planetary element or spider 56, the shaft 49 is provided with a friction brake 59.

In this embodiment of the invention, the prime mover for driving the gear mechanism 35 is an induction motor 61 of the squirrel cage type and is connected to the pinion shaft 53 by the coupling 62. The motor 61 is disposed to be connected to a power source such as conductors 63, by means of a switch 64 and an auto-starter 65.

In order to control the operation of the planetary element 56 of the differential gear mechanism 35, to obtain rotation of the drum 32 in the desired manner to reciprocate the pump plunger 6 a work device 66 is provided. As shown the driving sprocket wheel 68 of the work device 66 is connected for operation to the gear 35 by means of a chain 67. The work device 66 may be a pump for handling the fluid raised from the well or a compressor for forcing gas under pressure into the annular space formed by the casing 14 and tubing 3, each of which, operating as a control device, will be described in detail hereinafter.

The discharge of the work device 66, is controlled by a three-way rotary valve 69. Since valves of this type are well known in the art, a detailed view of this particular piece of apparatus has not been shown. However, the valve comprises an outer box or case, having an inlet opening and two discharge openings threaded to receive pipe. The case is bored to receive a rotatable cylinder member with ports and passages arranged so that by rotating the cylinder in one direction, the inlet will communicate with one discharge opening and close the other discharge opening, and, by rotating the valve in the opposite direction, the first

mentioned discharge opening is closed and the second mentioned opening is connected to afford communication with the inlet.

It will be readily understood that by utilizing a control device such as the rotary valve 69 the work device 66 may be loaded to such an extent as to cause the sun-gear wheel 47 of the gear mechanism 35 to remain stationary or run very slowly depending upon the amount of load imposed upon the planetary element 56 by the hoisting drum 32. When the motor 61 is rotating at a substantially constant speed in one direction only, the planetary element 56 will rotate in the same direction if the sun gear 47 is stationary or rotating at a slower speed than the driven sun-gear wheel 46, which will operate the hoist drum 32 and therefore the pump plunger. Under the same operating conditions for the motor, if the sun-gear wheel 47 is permitted to rotate reducing the load on the work device 66, the planetary element 56 will be reversed by the weight of the pumping string and consequently permits the drum 32 to unwind until the pump plunger reaches the bottom of its stroke.

It is therefore apparent that by automatically controlling the discharge and consequently the loading of the work device 66 in accordance with the number of drum rotations, the pump plunger will be periodically reversed without reversing the direction of the driving motor 61.

In order to control the operation of the three-way valve 69, in accordance with the rotation of the drum 32, an oscillator 71 is interposed therebetween and connected for operation as shown. Since a suitable oscillator has been described in detail in my co-pending application Serial No. 221,418, filed September 23, 1927, it is deemed sufficient to state that it comprises a driven gear train which upon a certain predetermined number of revolutions in either direction of rotation, causes a second element to be automatically revolved a partial revolution. The second element has considerable momentum and, therefore, is capable of exerting a comparatively high turning torque which may be utilized to operate a motor controller or a valve mechanism such as described hereinbefore.

As shown, the torque shaft upon which the sprocket 72 is secured is connected to the operating sprocket 73 of the three-way valve 69 by means of a chain 74.

The operation of the oscillator 71 is effected by connecting the gear train actuating sprocket 75 to the drum sprocket 42 by means of a chain 76. The ratio of one sprocket to that of the other being such as to allow a sufficient number of drum revolutions to make a complete pumping stroke before the torque shaft and sprocket 72 of the oscillator 71 is actuated to reverse the rotary valve 69.

It will be observed that the intake port of the rotary valve 69 is connected to the discharge port of the work device 66 by means of a pipe 77 and controlling valve 78.

5 A pressure gauge 79 is provided for indicating the discharge pressure of the fluid or gas through the pipe 77. The pressure readings of the gauge 79 will also indicate the pull on the chain 67 and on the wire line or cable 33 which will serve as an indirect measurement of the weight supported by the wire line 33 during pumping or hoisting operations.

10 It is to be understood that the invention as shown and described is suitable for pumping a well by either a mechanical lift method or by a combination mechanical lift and gas or air lift method as hereinbefore described, and, in addition, without change or modification 15 the system may be utilized to perform the necessary hoisting operations such, for example, as hoisting rods and tubing or making repairs which may require the use of hoisting equipment.

20 25 The operation of the system will first be described when operating as a combination mechanical pumping lift and gas lift system. In this event, the work device 66 is assumed to be a compressor for supplying gas or air under pressure to the casing 14. The intake 30 of the compressor 66, which is controlled by the valves 81 and 96, may be connected to any suitable source of natural gas supply such as tank 95, valve 81 being kept closed. One of 35 the discharge ports of the rotary valve 69 is connected to the casing cap 21, through the valve 85, T 86, pipes 87, 88 and 22. It will be observed that the T 86 in the discharge line is connected to a pressure tank 89, 40 through pipe 91 and pressure control valve 92 and that the other discharge port of the rotary valve 69 is connected to the pressure tank 89 through the valve 93 and pipe 94.

45 50 In order to set the system in operation, the clutches 38 and 39 are moved to the illustrated or disengaged positions, which allows the sprockets 41 and 42 to rotate freely on the drum shaft 36. The drum 32 is held in a fixed position by operating the brake band 43 to the holding position. The motor 61 may then be set in operation by closing the switch 64 and operating the auto-star or 65 in the usual manner. Since the sprocket 55, which is actuated by the sun gear 47, is connected to the 55 compressor, the load thereon is greater than the friction load of the sprocket 41, which is connected to the sprocket 45 by means of the chain 44, and therefore, the planetary element 56 of gear mechanism 35 will revolve 60 freely and no power will be transmitted to the compressor.

65 In order to set the compressor in operation, the brake 59 on the shaft 49 is actuated to its holding position, and stops the movement of the planetary element 56, and power from the

motor 61 is transmitted to the compressor through the pinion 52, gear wheel 51, sun gear 46, planetary pinions 57, sun gear 47, sprocket 55, and chain 67 to the sprocket 68 on the compressor crank shaft.

70 Since it is necessary to impose a heavy load upon the compressor 66 to effect the operation of the hoisting drum 32 as hereinbefore described, the compressor intake valve 96, discharge valves 78 and 93 are opened and the rotary valve 69 positioned by hand to discharge through valve 93 into the pressure tank 89.

75 80 The operation of the compressor 66 is continued in this manner until the pressure in the tank 89 increases to the required amount which is a higher pressure than that required within the casing 14. The rotary valve 69 is then rotated by hand so as to permit the compressor 66 to discharge through the valve 85 and pipes 87, 88 and 22 into the well casing 14. When the pressure within the casing 14 rises to a certain predetermined value the reducing valve 92 which controls the discharge 85 from the high pressure tank 89 is released and therefore the quantity of gas supplied to the casing 14 is also increased. It will be readily understood that since the discharge from the high pressure tank 89 is controlled by the existing pressure in the well casing 14 a comparatively slow discharge through the valve 92 will take place so long as the casing pressure does not fall below a certain value; also that the consequent pressure reduction in the tank 89 will not be great enough to relieve 90 the load upon the compressor 66 to such an extent as to prevent operation of the drum 32 as hereinbefore described.

95 100 105 In order to set the drum 32 in operation to actuate the pump plunger 6, the clutch 38 is closed to engage the sprocket 41, and the drum brakes 43 and 59 are released. Since the compressor 66 is discharging against a low pressure head in the casing 14, the planetary element 56 cannot revolve to operate the drum 32 as the power required to hoist the pumping string, comprising the plunger 6 and rods 8, is greater than the compressor load. Therefore, in order to load the compressor the rotary valve 69 is rotated by hand to again discharge into the tank 89 which causes the sun gear 47 to slow down and ultimately stop when the compressor load becomes greater than the pump load.

110 115 120 When the speed of the driven sun-gear wheel 46 becomes greater than the speed of the sun-gear wheel 47 which revolves in opposite direction, the planetary element 56 will revolve in accordance with the well known action of the differential.

125 130 Power is then transmitted through the planetary shaft 49, sprocket 45, chain 44 to the driving sprocket 41 of the hoist drum 32. The operation of the hoist drum 32 will raise the pump plunger 6 until it reaches

the top of the stroke, whereupon the oscillator 71 operates the rotary valve 69 to direct the discharge of the compressor 66 through the valve 85, into the well casing 14 and since the pressure in the well casing is relatively lower than that in the tank 89, the load on the compressor 66 is reduced.

The sun gear wheel 47 being free of the heavy compressor load, now rotates to permit the planetary element 56 to revolve in a reverse direction, being reversed by the power transmitted through the drum 32 by the weight of the pumping string. Since the energy stored by the pumping string during the upward stroke reaches a high value the power transmitted back through the planetary element 56 is applied directly to the sun-gear wheels 46 and 47 and therefore the sun-gear wheel 47 is driven at a speed controlled by the load at the compressor 66.

It will be readily understood that by regulating the discharge of the compressor 66 by adjusting the valve 85 the descending speed of the pumping string can be controlled as desired.

When the pumping string reaches the bottom of the stroke the oscillator 71 is operated and consequently the rotary valve 69 is actuated to again direct the discharge of the compressor 66 into the high pressure tank 89 which immediately causes the planetary element 56 to revolve and hoist the pump plunger 6 in the same manner as hereinbefore described.

It will be apparent that the operation of the well pump may be controlled by utilizing work device 66 as a reciprocating pump instead of as a compressor 66. In this event the pump 66 is shown connected directly to the casing cap 21 through pipes 82, 83, 84 and 22 and valve 23.

In operating the system, the motor 61 and pump 66 are set in operation as described hereinbefore with the hoisting drum 32 held in a fixed position by the brake 43. It will be readily understood that a quantity of fluid must be supplied for controlling the operation of the pump 66 until the well pump or plunger 6 has operated long enough to lift the fluid in the well to the surface. The pump 66 is, therefore, connected to the storage tank 95, through the valve 96 as shown. In this instance, the tank 95 contains a supply of liquid, preferably oil and by closing valves 81, 85 and 93, opening valves 78 and 90 and by positioning the rotary valve 69 to discharge through the valve 90 and pipe 97, a circulating system is provided for the pump.

In order to set the hoist drum 32 in operation, the brakes 43 and 59 are released and the clutches 38 and 39 actuated to the closed position. Discharge of the pump 66 is then restricted by moving the rotary valve 69 to close the port communicating with valve 90

and pipe 97, which as described hereinbefore causes the planetary element 56 which drives the drum 32 to revolve and actuate the pump plunger 6 to the top of its stroke. When the pump plunger 6 reaches the top of the upward stroke the oscillator 71 actuates the rotary valve 69 to permit the pump 66 to discharge through the circulating system as described hereinbefore and the planetary element 56 automatically reverses to permit the downward stroke of the plunger 6.

The descending speed of the plunger 6 is also controlled in this instance by regulating the discharge of the pump 66 by means of the valve 90.

The operation of the system continues in this manner until the fluid which is being raised from the well reaches the surface as evidenced by discharge through the vent valve 31, in which case the intake port of the pump 66 is connected to the casing cap 21 by opening the valves 23 and 81. Since the fluid in the storage tank 95 is no longer required for controlling the operation of the pump 66, the valve 96 is closed, and therefore the fluid from the well is pumped directly into the storage tank 95.

It will be readily understood that the operation and control of the pump 66 will be the same as described hereinbefore, the pump now receiving fluid from the well instead of from the tank 95 and discharging under control of the rotary valve 69 into the storage tank 95 or into any other suitable receptacle, such as storage tank 89 as by opening valve 93. Furthermore, opening valves 27 and 92 will permit the well fluid to flow through tubing cap 26 into tank 89.

It will be readily understood that the system as shown may be utilized at any time to perform hoisting operations, such for example as removing the rods or tubing from the well, by using the fluid in the tank 95 for controlling the operation of the pump 66 as hereinbefore described in detail. However, in this instance the discharge of the pump 66 is controlled by positioning the rotary valve 69 to discharge through the valve 90 and pipe 97, with the oscillator 71 disconnected from the drum 32, and then alternately opening and closing the valve 90 to obtain lowering and hoisting operation of the drum 32.

It will be apparent that in operating the system as set forth hereinbefore, the kinetic energy of the descending pump string comprising the rods 8 and plunger 6, will be transmitted through the reduction gear mechanism 35 to the motor 61, as well as to the work device 66. This will tend to overspeed the motor 61 thereby providing a regenerative braking action which will limit the motor speed and return electrical energy to the power circuit.

From the foregoing explanation it will be apparent that a pumping system is provided

wherein an ordinary plunger pump such as is commonly used for pumping oil wells and the like, is operated in accordance with the best practice, by utilizing an auxiliary work device for controlling the operation of the pump and in addition for doing useful work such for example as pumping fluid or compressing gas or air for various uses. Since the principle of the invention is such 5 as to utilize the energy stored in the moving parts of the pump for operating the auxiliary work device the efficiency of the system as a whole is high, which is a very desirable feature.

10 15 While the illustrated example constitutes a practical embodiment of my invention, I do not limit myself to the exact details herein illustrated, since modifications of the system can be made without departing from the 20 spirit of the invention as defined in the appended claims.

I claim as my invention:

1. In a well pumping system, the combination of: two concentric well casings, an intermediate coupling for the outer of said casings, said coupling being arranged to receive the lower end of the inner casing and to provide a common fluid chamber for both said casings, a pump disposed in said outer 30 casing below said coupling and actuated by a source of power at the top of the well, and means connected to the upper end of one of said casings for forcing compressed gas through the last named casing into the afore- 35 said chamber.

2. In a well pumping system the combination of: two concentric well casings packed fluid tight against each other at the top of the well and having unrestricted fluid communication with each other at the lower end of the inner of said casings, a mechanically operated pump disposed in the outer casing below the inner casing for lifting the well fluid in said casings, said pump being operatively connected to power driven mechanism at the top of the well, a motor for operating said mechanism, and means connected to the upper end of one of said casings for forcing compressed gas through said 50 casings.

3. In a pumping system, in combination, a well casing, mechanically operated pumping means disposed in the casing, pressure pumping means for assisting the mechanically operated pumping means in lifting fluid from the casing, a motor for supplying energy to said pumping means, and intermittently actuated means for jointly controlling the action of the mechanically operated pumping means and the pressure pumping means.

4. In a pumping system, in combination, a well casing, mechanically operated pumping means disposed in the casing, pressure pumping means for assisting the mechanically operated pumping means in lifting fluid from

the casing, a motor for supplying energy to said pumping means, power transmission means connected between the motor and the mechanically operated pumping means, and means actuated in accordance with the operation of said mechanically operated pumping means for controlling the operation of the power transmission means and the pressure pumping means.

5. In a system for pumping oil from wells, in combination, a mechanically operated pump provided with a plunger, a motor for actuating the pump, a compressor for delivering compressed fluid, means for utilizing the motor for actuating the compressor during a pumping stroke, means for utilizing the pump plunger for operating the compressor on the down stroke, and means for delivering the compressed fluid into the well to cooperate in the pumping operations.

6. In a pumping system, in combination, a well casing, a plunger pump disposed in the casing, a motor for operating the plunger pump, means interposed between the pump and motor, for controlling the operation of the pump, said control means including a hoisting drum for operating the pump and a differential gear mechanism for controlling the operation of the hoisting drum, and means operatively connected with the differential gear mechanism for compressing and forcing lifting fluids into the well casing, said means being disposed to control the operation of the gear mechanism to effect the operation of the pump.

7. In a pumping system, in combination, a well casing, a plunger pump disposed in the casing, a motor for operating the plunger pump, means interposed between the pump and motor, for controlling the operation of the pump, said control means including a hoisting drum for operating the pump and a differential gear mechanism for controlling the operation of the hoisting drum, a compressor connected in the pumping system for forcing compressed lifting fluid into the well casing and means disposed to control the discharge of said compressor and thereby effect the operation of the differential gear mechanism for actuating the plunger pump.

8. In a pumping system, in combination, a well casing, a plunger pump disposed in the casing, a motor for operating the plunger pump, means interposed between the pump and motor, for controlling the operation of the pump, said control means including a hoisting drum for operating the pump and a differential gear mechanism for controlling the operation of the hoisting drum, a compressor connected in the pumping system for forcing compressed lifting fluid into the well casing and means actuated in accordance with the rotating of the hoisting drum dis-

posed to vary the discharge of the compressor thereby varying its load to effect the operation of the differential gear mechanism for actuating the plunger pump.

⁵ In testimony whereof, I have hereunto subscribed my name this 21st day of February, 1928.
